CLAIM

The ornamental design for a cup, as shown and described.

DESCRIPTION

FIG. 1 is a top perspective view of a cup showing my new design;

FIG. 2 is a bottom perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof;

FIG. 8 is a bottom plan view thereof;

FIG. 9 is a cross-sectional view thereof taken, along 9-9 of FIG. 3;

FIG. 10 is a detail view thereof, according to reference 10 of FIG. 9;

FIG. 11 is another top perspective view thereof, showing the cup stacked within additional exemplary cups; and,

FIG. 12 is another left side elevation view thereof, showing the cup stacked within additional exemplary cups.

The broken lines depict unclaimed features of the cup as well as environmental features that form no part of the claimed design.
